United States Patent Office.

T. G. SPRINGER, OF CLINTON, IOWA.

Letters Patent No. 89,802, dated May 4, 1869.

IMPROVEMENT IN PRODUCING GAS FOR HEATING AND LIGHTING.

The Schedule referred to in these Letters Patent and making part of the same.

To all whom it may concern:

Be it known that I, T. G. SPRINGER, of Clinton, in the county of Clinton, and in the State of Iowa, have invented certain new and useful Improvements in Burner-Attachment for Gas-Machines; and do hereby declare that the following is a full, clear, and exact description thereof, reference being had to the accompanying drawings, and to the letters of reference marked thereon.

My invention relates to that class of machines in which gas is generated from gasoline, or other suitable fluid, and consists in connecting the heaters with the generating-chamber, instead of at a point above the mixing or air-chamber, as heretofore practised; also in filling the generating-chamber with plaster Paris, or other suitable material, having a series of perforations or holes; and, also, in providing the tube above the generating-chamber at a suitable point, with an inside funnel-shaped tube; all of which will be hereinafter fully set forth.

In order to enable others skilled in the art to which my invention appertains, to make and use the same, I will now proceed to describe its construction and operation, referring to the annexed drawings, which form a part of this specification, and in which—

Figure 1 is a longitudinal vertical section of the tube and burner;

Figure 2, a side view of the burner; and

Figure 3, a cross-section of the generating-chamber.

A represents the lower portion of the tube leading from the reservoir in which the gasoline is contained.

The lower end of said tube is bent in a horizontal shape, and to the other end of which the burner B is attached.

In the horizontal portion of the tube A, the gas is generated from the gasoline by the heat from the flame in the upper end of the burner.

Usually this heat has been communicated by wings or heaters connected to the burner at or near the upper end, but as the gas cannot, by such means, become sufficiently heated to overcome the cold air passing up with the gas through the mixing or air-chamber in the burner, the light would be feeble in a greater or less degree. Even in cold rooms, the heat would, in some instances, not be sufficient to generate any gas at all.

To overcome this difficulty, I connect the wings or heaters C O with the end of the burner below the mixing-chamber, where the said burner is attached to

the tube, thus, in fact, communicating the heat direct to the generating-chamber.

By this means the generating-chamber will at all times be hot enough to generate gas, and the gas itself will be, so to say, superheated, so as to overcome the coldness of the atmosphere while passing through the mixing-chamber in the burner.

The horizontal portion of the tube A, the whole or part of which constitutes the generating-chamber, is filled with plaster Paris, or other suitable material, perforated, as shown in fig. 1, by which a larger amount of heating-surface is obtained than when said chamber is not so filled, thus increasing both the quantity and quality of the gas generated.

D represents the stop-cock for regulating the flow of gasoline from the reservoir.

Just below this stop-cock I insert a small funnel-shaped tube, a, through which the gasoline flows.

In the machines heretofore used, when a certain amount of gas has been generated, the upward pressure of the gas and the downward pressure of the gasoline invariably cause a flickering, unsteady light, but by using the tube this is entirely remedied, as, it will be seen, the gasoline passes downward, entering the tube a at its wider end, and passes out through the narrower end, while the upward pressure of the gas has only the small, narrow end of said tube to act upon; hence the pressure from above overcomes or counteracts the pressure of the gas upward, making a steady light.

Having thus fully described my invention,

What I claim as new, and desire to secure by Letters Patent, is—

1. Connecting the wings or heaters of a gas-burner with the generating-chamber, or at some point between the generating and the mixing-chambers, substantially as and for the purposes herein set forth.
2. Filling the generating-chamber of a gas-machine with perforated plaster Paris, or its equivalent, substantially as and for the purposes herein set forth.
3. Providing a gas-pipe with an inside funnel-shaped tube, for the purpose of preventing a flickering or unsteady light, substantially as herein set forth.

In testimony that I claim the foregoing, I have hereunto set my hand, this 6th day of March, 1869.

T. G. SPRINGER.
